UNITED STATES PATENT OFFICE.

DE WITT C. GOODRICH, OF NATIONAL MILITARY HOME, KANSAS.

BRACE-BIT BORING-TOOL.

1,072,328.

Specification of Letters Patent.

Patented Sept. 2, 1913.

Application filed February 10, 1912. Serial No. 676,714.

To all whom it may concern:

Be it known that I, DE WITT C. GOODRICH, a citizen of the United States, residing at National Military Home, in the county of 5 Leavenworth and State of Kansas, have invented new and useful Improvements in Brace-Bit Boring-Tools, of which the following is a specification.

This invention relates to a directing implement for boring bits.

In carrying out my invention it is my purpose to provide a simple and effective device whereby bits or augers may be directed at any desired angle. I also propose to 10 provide an apparatus of this character which is extremely simple in construction, comprising few parts, which is accurate and which may be constructed at a minimum cost.

With the above objects in view, the invention resides in the novel construction, combination and arrangement of parts set forth in and falling within the scope of the appended claims.

In the drawings, Figure 1 is a top plan view of a device constructed in accordance with the present invention. Fig. 2 is a front elevation of the same. Fig. 3 is an end view of the same. Fig. 4 is a plan view of a 25 slightly modified form of the device. Fig. 5 is a sectional view upon the line 5—5 of Fig. 1. Fig. 6 is a sectional view upon the line 6—6 of Fig. 1. Fig. 7 is a sectional view upon the line 7—7 of Fig. 1. Fig. 8 is 30 an end elevation of the device illustrated in Fig. 4.

Referring now to the drawings in detail the numeral 1 designates the base member, which is preferably of a rectangular formation and which may be constructed of any 35 desired material. The base 1, adjacent its transverse edges is preferably formed with ribs 2, the same extending the entire width of the base.

The numeral 3 designates a plate which is 40 adapted to rest upon the base 1. This plate adjacent its transverse edges is provided with depressed portions or channels 4, the latter adapted to be received upon the ribs 2.

The plate 3 is also preferably of a rectangular formation, and as illustrated in Fig. 1, the said plate 3 is formed with oppositely arranged pairs of elongated slots or openings 5, the same being positioned directly above the channels 4.

The numeral 6 designates headed screw

members which pass through the slots 5 and which engage within threaded openings provided in the base 1, and whereby the plate may be secured in an adjustable position 60 upon the base 1.

The numeral 7 designates a semi-circular member, the same having its upper face provided with graduation marks as designated by the numeral 8. This semi-circular member or segment is provided with a slot or opening 9, which is concentric with the outer or curved edge of the said member 7, and passing through this curved slot 9 is a headed threaded member 10. This member 10 is adapted to engage within a threaded recess provided upon a substantially V-shaped guide member 11, said guide member being pivoted to the segment 7 as at 12. The plate 3 as well as the base 1 are 65 each provided with a centrally arranged elongated opening 13 through which the bit or auger is adapted to project when engaging the material to be operated upon. In this connection it may be stated here that 70 75 the auger or bit is placed within the guide 11 after the said guide has been adjusted upon the segmental member 7, and it will of course, be understood that the said guide will direct the bit to a desired angle at 80 85 which the said bit is to be operated.

The central portion or what may be termed the apex of the V-shaped guide 11 is provided with a graduation or mark 14, the latter adapted to register with any of the 90 graduations 8 upon the said member 7, so that the desired angle may be readily attained. In the said figures of the drawings the segmental member 7 is provided adjacent the lower edges with rearwardly extending flattened arms 15, the same being each formed with a longitudinally extending slot 16, and the plate 3 is provided with graduation marks 17, which are arranged adjacent the outer longitudinal edges of the 95 said arms 15. The outer edges of the arms 15 are likewise provided with graduations 18.

The numerals 19 designate headed threaded members, the threaded portions of which 100 passing through the slots 16 and engaging within threaded openings provided in the plate 3. The shoulders or heads of the said members 19 are adapted to contact with the plates 15 adjacent the slotted openings thereof, to compress the same upon the plate 3, and thus permit of the adjustment of the 105 110

2
segmental member 7 with relation to the said plate 3.

In Figs. 4 and 5 the device is substantially similar to that heretofore set forth except that in these figures the segmental member 7' is formed with a rectangular rearwardly extending plate or base 20, the same being provided adjacent its end edges with elongated slots corresponding with the slots 16 in the arms 15. The outer edges of the member 20 are preferably beveled as at 22 and are provided with graduation marks 23 which correspond with similar marks 24 provided upon the plate 3' the plate in this instance 15 is also centrally formed with an elongated opening for the passage of the bit.

Having thus described the invention, what I claim is:—

1. In a device for the purpose set forth, a base having transversely arranged ribs, a plate having its under face recessed to engage with the ribs, means for adjustably sustaining the plate upon the ribs of the base, the said plate being centrally provided 25 with an elongated opening, a segmental member arranged upon the plate, said member being provided with rearwardly extending graduated portions, means for adjustably sustaining the segmental member upon 30 the plate, a pivoted guide member upon the segmental member, and means for retaining the said guide member at an angular adjustment upon the segmental member.

2. In a device of the class described, a base, said base having a central opening, a plate adjustably secured upon the base, said plate having a central opening which registers with the opening in the base, a seg-

mental member adjustably connected with the plate and arranged at a right angle thereto and transverse the openings of the plate and base, a guide member concentrically pivoted to the segmental member, and means co-acting with the guide and segmental member for sustaining the guide 45 when swung upon its pivot upon the segmental member.

3. In a device for the purpose set forth, a substantially rectangular base, a longitudinally adjustable plate upon the base, the said plate being centrally provided with an opening, a segmental member for the plate, said member having angularly arranged rearwardly extending portions which rest upon the plate, the said portions being provided with elongated slots, headed threaded members passing through the slots, the segmental member having a concentrically arranged opening disposed adjacent its periphery, a guide member pivotally connected to the segmental member at the axial center of the said member and disposed directly above the slot of the opening of the plate, and a headed threaded member passing through the concentric slot of the segmental member and engaging with the guide member to retain the said guide at a desired angle with relation to the segmental member and to the base.

In testimony whereof I affix my signature 70 in presence of two witnesses.

DE WITT C. GOODRICH.
